UNITED STATES PATENT OFFICE

123,046

DESIGN FOR AN INDICATOR GAME DEVICE

Alfred H. Behrman and Levi H. Eckhardt, Baraboo, and Franklin H. Avers, Portage, Wis.

Application March 30, 1940, Serial No. 91,366

Term of patent 7 years

To all whom it may concern:

Be it known that we, Alfred H. Behrman, Levi H. Eckhardt, and Franklin H. Avers, citizens of the United States, residing respectively at Baraboo, in the county of Sauk and State of Wisconsin, Baraboo, in the county of Sauk and State of Wisconsin, and Portage, in the county of Columbia and State of Wisconsin, have invented a new, original, and ornamental Design for an Indicator Game Device, of which the following is a specification, reference being had to the accompanying drawing forming part thereof.

In the drawing:

Fig. 1 is a plan view of the indicator game device showing our new design; and

Fig. 2 is an elevational view thereof.

We claim:

The ornamental design for an indicator game device, substantially as shown.

ALFRED H. BEHRMAN.
LEVI H. ECKHARDT.
FRANKLIN H. AVERS.
